UNITED STATES PATENT OFFICE.

FRED McMILLAN, OF BEAVER DAM, WISCONSIN.

ROPE-WEAVING MACHINE.

Application filed November 1, 1921. Serial No. 511,978.

To all whom it may concern:

Be it known that I, FRED McMILLAN, a citizen of the United States, and resident of Beaver Dam, in the county of Dodge and State of Wisconsin, have invented certain new and useful Improvements in Rope-Weaving Machines; and I do hereby declare that the following is a full, clear, and exact description thereof.

10 My invention has for its object to provide a simple, economical and effective portable rope weaving machine particularly for farmer's use, and in solving the problem of a weaving machine of this general type, particular thought and experiments has been directed towards producing a machine which can be manufactured at a normal cost and which will not deteriorate due to rough usage.

20 With the above object in view the invention consists in certain peculiarities of construction and combination of parts as will hereinafter be set forth in the accompanying drawings and subsequently claimed.

25 In the drawings,

Figure 1 represents a face view of the rope strand twisting element constituting part of my invention,

Figure 2, a cross section of the same, the section being indicated by line 2—2 of Figure 1.

Figure 3, a detailed plan view showing the construction of one of the twisting elements.

35 Figure 4, a face view of a thread holder unit to be associated with the thread twisting unit, and

Figure 5, a diagrammatic plan view illustrating the apparatus in use, having a strand 40 of binder twine or like thread wound back and forth upon the elements preparatory to twisting.

Referring by characters to the drawing, 1 represents a portable frame having pairs of 45 legs 2 extending therefrom for clamping engagement with a fixture 3, which fixture may be the tail board of a wagon or other convenient point of anchorage. The frame proper is longitudinally divided to form a removable cap piece 1', whereby the trunnions 4 of a series of hooks may be conveniently journaled and assembled, the said trunnions being mounted in bushings 4'. The hooks 5 are of the ordinary open 55 mouth type and the rear ends of the trunnions terminate with crank ends 5',

which ends are journaled in a split pitman 6, the same being provided with a handle 6' whereby it is manually actuated to produce a simultaneous rotary motion of the 60 series of hooks.

The above described mechanism constitutes a thread twisting unit, the other unit of the apparatus being a thread holder 7, as illustrated in Figure 4 of the drawings. The thread holder, as shown, is so positioned with relation to the thread twisting unit (Figure 5), that it is aligned with the twisting unit and spaced therefrom the length of the rope which is to be manufactured, it being understood that the holder is anchored approximately central with relation to the gang of hooks.

As shown in Figure 4, the twisting unit is anchored in a socket 8, or it may be fastened in any other suitable manner, as by screws or nails. The upper portion of the thread holder is formed with a reduced thread guiding neck 9 from which neck extends upwardly a pair of thread guiding 80 prongs 10, the crotch 10' of the prongs being spaced to also form a thread guide, whereby said thread, when wound from the several hook units to the thread holder, will be spaced into a series of parallel groups 85 corresponding to the number of hooks.

For example, referring to Figure 5, the thread may be started from the hook X in the direction of the arrow and it is initially wound about the neck 9 to the last of the series of hooks, as indicated at Y. The thread is then returned to the thread holder, as indicated by the arrows, and coiled about one of the prongs. From thence it is coiled about the intermediate hook Z and back over 95 the opposite prong. The crotch in this winding serves to hold the strands of the hook Z in parallel relation. The strand, after being passed over the next prong, is trained over the intermediate hook Z' and 100 back into the crotch of the thread holder and over the inside of the prong downwardly to the neck 9 and from thence to the hook X where it is joined in any suitable manner to the initial end of the strand. This winding 105 can be repeated an indefinite number of times, depending upon the strength or diameter of the rope required.

After the winding of the thread has been complete, the operator rotates the pitman 6, 110 causing each group of thread units to be tightly coiled, due to the simultaneous rota-

tions of the hooks. After the twisting operation has been completed, four rope strands will result, in this particular exemplification of my invention, and when the 5 rope strands have been removed, the twist or torsion thereof will cause the strands to produce an ordinary standard coil or twisted rope having four strands. Obviously 10 the number of hooks can be varied indefinitely and also the nature of the thread to be formed into a rope. However, in practice among farmers, it is preferable to utilize the standard type of binder twine.

From the foregoing description it will be 15 seen that individuals can readily manufacture, by manual power, ropes necessary for all of their requirements from material at hand.

While I have shown and described one 20 simple exemplification of my invention, it is understood that I may vary the details of construction within the scope of the claims.

I claim:

A portable hand power rope forming apparatus comprising a frame having downwardly extending clamping legs adapted to rigidly engage a fixture, and having a split body including a main part and a removable part having bearings therebetween, a series of hooks located on one side of said frame 25 and having shanks positioned within said bearings, cranks located upon the opposite side of said frame from said hooks and formed integrally therewith, a pitman 30 formed of two members clamped together and having bearings therebetween for receiving said cranks, and a handle carried by said pitman.

In testimony that I claim the foregoing I have hereunto set my hand at Beaver Dam, 40 in the county of Dodge and State of Wisconsin.

FRED McMILLAN.
